UNITED STATES PATENT OFFICE.

JAMES H. TOZER AND WILLIAM TOZER, OF LONDON, ENGLAND.

PART OF THE PERMANENT WAY OF RAILWAYS.

SPECIFICATION forming part of Letters Patent No. 349,913, dated September 29, 1886.

Application filed June 16, 1886. Serial No. 205,372. (No model.)

To all whom it may concern:

Be it known that we, JAMES HONIBALL TOZER and WILLIAM TOZER, both of London, England, have invented certain new and useful 5 Improvements in Parts of the Permanent Way of Railways, of which the following is a specification.

Our invention relates to the permanent way of railways, and has reference more especially 10 to the securing of the chairs to the sleepers, and particularly to sleepers made of wrought iron or steel.

Our invention provides chairs with two or other number of projections or parts, which, 15 by a turning movement, when the chair has been placed upon the sleeper at an angle to the normal position, become tightly jammed or wedged with corresponding parts of the sleeper, whereby a perfectly firm and secure 20 fastening of the chair to the sleeper is formed, no additional fastening being necessary.

The manner in which we prefer to carry out our invention is as follows: We make the chair with wedge-shaped or beveled ends, and with 25 a pin forming a pivot, upon which the chair can be turned, and we construct the sleeper with lips or lugs to receive the beveled ends of the chair, and with a hole to receive the pin. The lips or lugs can be pressed out of the solid 30 metal of the sleeper. In order to fix the chair, it is first placed upon the sleeper at an angle to the normal position, and with the pin in the hole. The chair is then turned upon the pin, so as to bring the beveled ends under the lips 35 or lugs, with which they therefore become tightly jammed. If preferred, the bevels may be on the lips, instead of upon the chair ends, or both may be beveled.

The annexed drawings illustrate our invention.

Figure 1 is a section through the center of the chair; Fig. 2, an end elevation, and Fig. 3 a plan showing a sleeper, chair, and rail, the chair being of the form we prefer to adopt when 45 made of wrought-iron or wrought-steel, and to receive a flat-bottomed rail. Fig. 4 is a section similar to Fig. 1, and showing a modification. Figs. 5, 6, and 7 are views answering to Figs. 1, 2, and 3, and showing our invention 50 as adapted to a double-headed or H rail.

Referring first to Figs. 1, 2, and 3, *a* is the

sleeper, which, as shown, is a metal sleeper of inverted-trough section. *b* is the chair, and *c* the rail.

d d are two lips or lugs pressed out of the 55 solid metal of the sleeper, and at *e* is a hole in the sleeper.

f is a pin on the chair to enter the hole *e*. The ends of the chair are beveled, as is best seen in Fig. 2, and the bevel is preferably 60 double—that is to say, the first or outer portion, *g*, is beveled to a certain degree—say one in ten—while the second or inner portion, *g'*, is beveled in a less degree—say one in thirty—but, if desired, the bevel may be the same 65 throughout.

When it is required to fix the chair, it is first placed upon the sleeper at an angle to its normal position, (see the dotted lines in Fig. 3,) and with the pin *f* in the hole *e*. The chair is 70 then turned upon the pin, so as to bring the beveled ends *g g* under the lips or lugs *d d*, with which they become tightly jammed. The beveled chair ends *g g* and the lips *d d* should be so arranged relatively to each other that considerable force is required to drive the beveled 75 ends home. The lips *d d* may be beveled as well as or instead of the chair ends *g g*. It is preferred, but not essential, to bevel both the lips and the chairs.

h represents a metallic key-fastening for fixing the rail in the chair. If wooden keys are to be used for this purpose, the chair-jaw should be of the form represented in Fig. 4, or approximately so. If the chair be made of cast- 85 iron, instead of wrought iron or steel, it will be of similar form, but of fuller proportions throughout.

Figs. 5, 6, and 7 illustrate our invention as adapted to a double-headed or bull rail. By 90 preference we make the chair of cast-iron, of the form shown. It is secured to the sleeper in the same manner as that shown in Figs. 1, 2, and 3.

The same letters of reference indicate corresponding parts.

i is a pad or layer of felt or other suitable material between the chair and the sleeper to lessen jar or concussion. The use of this pad is optional. The pin *f* is not necessarily 100 placed in the middle of the chair, as shown. This vertical pin *f* on the under side of the

chair, and fitting into a corresponding hole in the sleeper, serves to keep the gage of the rails, and receives the thrusts and strains.

What we claim, and desire to secure by Letters Patent, is—

1. A railway-chair constructed with inclined or beveled provisions on its opposite sides or ends, adapted by a twisting movement to be engaged with corresponding fastening projections on a sleeper, substantially as set forth.

2. The combination, with a sleeper having opposite projections, of a chair constructed with corresponding inclines or beveled provisions on its opposite sides or ends, adapted to be engaged with the projections on the sleeper by a twisting movement of the chair relatively to the sleeper, substantially as set forth.

3. The combination, with a sleeper having opposite overhanging projections, of a chair

having corresponding inclines adapted to enter beneath said projections laterally by a twisting movement of the chair and a swivelled or pivotal connection between said chair and sleeper, substantially as set forth.

4. The combination, with a sleeper and chair having reciprocal locking provisions adapted to be engaged by a twisting movement of said chair, of a pivot-pin on one of said parts and a socket therefor in the other, substantially as set forth.

In witness whereof we have hereunto signed our names in the presence of two subscribing witnesses.

JAMES H. TOZER.
WILLIAM TOZER.
